UNITED STATES PATENT OFFICE.

SOLOMON KARPEN, OF CHICAGO, ILLINOIS.

SOFA-BED.

949,374.

Specification of Letters Patent. Patented Feb. 15, 1910.

Application filed March 26, 1909. Serial No. 825,973.

To all whom it may concern:

Be it known that I, SOLOMON KARPEN, a citizen of the United States, residing at Chicago, in the county of Cook and State of Illinois, have invented a new and useful Improvement in Sofa-Beds, of which the following is a specification.

My invention relates particularly to combination sofas and beds, or combination couches and beds, in which a foldable mattress-frame, or foldable bed-frame, is normally housed within the main frame beneath the seat of the sofa and equipped with a foldable wire mattress, or spring bed-bottom, the parts being so related as to afford room between the sections of the folded bed-frame and bottom for the bedding, *i. e.*, the mattress-pad, bed-linen and covers.

My primary object is to provide an improved construction of the character indicated possessing the qualities of simplicity, durability and handiness of operation, while affording a comfortable sofa of pleasing appearance when in the sofa form and a thoroughly comfortable bed when in the bed form.

It may be preliminarily stated that in the preferred construction of the invention which is illustrated in the accompanying drawings, there are employed a main frame; a stationary back carried thereby; a seat pivotally supported near its rear edge on the main frame and adapted to assume a standing position adjacent to the sofa-back; and a foldable mattress-frame normally housed within the main frame beneath the seat, mounted on a carriage or slides, so as to be bodily movable in a forward direction; and connections between the rear portion of the seat and the carriage, or slides, whereby the foldable mattress-frame will be bodily carried forwardly automatically when the seat is raised to the standing position and will be bodily carried rearwardly automatically when the seat is lowered to the normal position for use in a sofa. As has been indicated, the mattress-frame is preferably equipped with a flexible mattress or bed bottom which is unfolded or spread in the operative position when the device is converted to bed form; and the mattress-pad, or mattress proper, and other bedding, including the bed-linen and covers, are secured in position and folded between the sections of the foldable mattress-frames, so that the bedding will be spread out with the mattress or

flexible bed bottom when the device is converted to bed form.

In the accompanying drawings—Figure 1 represents a sectional view of my improved combined sofa and bed, illustrating the device in unfolded condition, that is, in bed form, the flexible bed bottom and bedding not being shown in this view, however; Fig. 2, a broken perspective view illustrating the manner in which the sections of the foldable mattress-frame employed are connected together and trussed; Fig. 3, a view similar to Fig. 1, but showing the device in sofa form; Fig. 4, an enlarged broken sectional view taken as indicated at line 4 of Fig. 3 and illustrating the manner in which the roller-equipped slides or carriage employed are connected with the horizontal guides or track carried by the inner surfaces of the main frame; Fig. 5, a broken perspective view showing the front portion of one of said slides, and portions of the links connected therewith; and Fig. 6, a broken plan sectional view taken as indicated at line 6 of Fig. 1.

In the preferred construction, A represents the main frame; B, a sofa-back fixedly secured between the end-standards thereof; C, a swinging sofa-seat pivotally connected near its rear edge with the end-standards of the main frame; D, a forwardly and rearwardly movable carriage mounted on the main frame; and E, a folding bed mounted on the carriage D.

The frame A may be of any suitable construction. In the construction illustrated, the frame comprises wooden end-standards 1 which constitute the arms of the sofa; a rear connecting member 2; and a bottom connecting member 3. As will be understood, the end-standards may be made plain or as ornamental as desired.

The back B may be attached in any preferred manner. As shown, it fits between the end-standards 1 and is rigidly connected therewith by angle-bars 4. The position of the back is preferably such that it inclines rearwardly and upwardly, as shown. Ordinarily the back comprises a frame equipped with an upholstered pad 5, which is indicated by dotted lines.

The seat C may be of any preferred construction. As shown, it comprises a spring-supporting frame 6 which usually is equipped with an upholstered pad 7, shown by dotted lines. The end members of the

frame 6 are connected by pivots 7 with the end-standards 1 of the main frame. The pivotal connections are preferably located a short distance in advance of the rear edge of the frame 6, and the pivotal connection may be of any desired form.

The carriage D, in the form illustrated, comprises a pair of slides 8 which are equipped with rollers 9 adapted to travel in horizontally disposed guides or run-ways 10 applied to the inner surfaces of the end-standards 1 of the main frame near the lower ends of said end-standards. As shown in Fig. 4, each slide 8 is fitted with headed studs 11 upon which the rollers 9 are mounted. Each track 10 comprises a member 12 equipped at its upper and lower edges with in-turned flanges 13, the flanges 13 carrying vertical flanges 14 which are turned toward each other. The construction provides a lateral slot 15 through which the studs 11 and the shanks of the rollers extend. Otherwise stated, each track is provided with a T-slot adapted to accommodate the rollers carried by the corresponding slide 8. Each slide 8 is provided at its lower edge portion with inwardly-struck members or stops 16 adapted to support the bed in its folded condition.

The folding bed E comprises a rear mattress-frame section 17 carried by pairs of links 18 and 19 mounted on the slides 8; an intermediate section 20 connected by pivots 21 with the front end of the section 17; a front section 22 connected by pivots 23 with the front end of the section 20; legs 24 connected by pivots 25 with the front end of the front section 22; links 26 whose front ends are connected by pivots 27 with upward extensions of the legs 24 and whose rear ends are connected by pivots 28 with the intermediate section 20; links 29 whose front ends are connected by pivots 30 with the intermediate section 20 and whose rear ends are connected by pivots 31 with the upward extensions of the front links 18; and a truss 32 connecting the end members of the intermediate section 20. The slides 8 are joined to the rear portion of the seat frame 6 by links 33, the rear ends of said links 33 being connected by pivots 34 with said seat frame, and the front end of said links being connected, by pivots 35, with the front ends of the slides 8. The slides 8 are provided at the upper portions of their front ends with inwardly-struck members or stops 36 adapted to engage the links 18 when the latter are in their standing position. For convenience, the front ends of the links 33 are curved downwardly to adapt them for connection with the slides 8 in front of the stops 36. A folding front piece, or front board, 37, is connected with the main frame and joined by links 38 to the front portions of the links 33. The front piece 37 may be

composed of a board and an upholstered pad 39, indicated by dotted lines. The front piece is equipped near its lower edge with pivots 40 connected with the lower front corners of the end-standards of the main frame.

As will be clearly understood from Fig. 1, the links 18 and 19 are parallel links adapted to maintain the rear mattress-frame section 17 in parallel relation to the slides 8. The upper ends of the links 18 and 19 are connected with the end members of the rear mattress-frame section 17 by pivots 41, and the lower ends of said links are connected with the slides 8 by pivots 42. The links 19 are provided at their lower ends with oblique extensions 43 which are connected by springs 44 with oblique extensions 45 with which the rear ends of the slides 8 are equipped. The tendency of the springs 44 is to maintain the bed in the extended position shown in Fig. 1, and it will be understood that the springs assist in the unfolding operation.

The truss 32 comprises vertical arms 46 whose lower ends are connected by a member 47, the members 46 and 47 being connected by braces 48. The upper ends of the arms 46 are connected with pivots or bolts 49 carried by bracket members 50 secured to and projecting beneath the end members of the intermediate bed section 20.

The mattress-frame is preferably formed of angle-bars, the front and rear sections being of U-shape, and the end members forming the intermediate section being straight members connecting the extremities of the ends of the U-shape members. The parts are so related that in the unfolded condition the members of the section 20 have their horizontal flanges resting upon the horizontal flanges of the rear section, as will be clearly understood from Figs. 1 and 2, so that the intermediate section will be supported by cantilever action. The truss 32 hangs out of the way of the bed when the bed is extended, and hangs parallel with the intermediate section 20 so as to be out of the way of the front piece 37 when the structure is in the folded condition.

The mattress-frame has attached thereto a flexible bed-bottom, or wire mattress, 51, shown in Fig. 6. The pad, or mattress proper, the bed-linen and the covers are usually secured in position while the bed frame is in the extended position, and folded with the bed frame when the latter is folded. The bedding is not shown in the drawings, however, being omitted for clearness of illustration. By reference to Fig. 3, it will be observed that ample room is afforded between the rear section 17 and front section 22 for accommodating the bedding when the mattress-frame is folded.

The operation will be readily understood

from the foregoing description. Assuming the structure to be in sofa form, as illustrated in Fig. 3, the seat may be turned about the pivots 7 so as to assume the standing position shown in Fig. 1. In the operation of moving the seat to the standing position, the links 33 operate to move the carriage D, and the folded bed E mounted thereon, forwardly, the front-piece 37 being automatically swung downwardly out of the way in the same operation. The bed may then be unfolded by swinging the upper (front) bed section 22 forwardly, thereby extending the bed sections and causing the parallel links 18 and 19 to elevate the lower (rear) bed section. As has been indicated, the springs 44 aid in this operation. In the unfolding operation, the links 26 operate to automatically extend the legs 24 which support the front portion or free edge portion of the front frame section 22. Assuming the bed to have been properly made up before the structure was folded into sofa form, the bedding will be spread out when the bed is unfolded in the manner just described. Prior to the operation of converting to sofa form, the bed is made up and the bedding secured to the mattress-frame. The bed is then folded, the rear section at the same time dropping to the plane of the slides 8. The seat is then swung forwardly and downwardly to its horizontal position, in which operation the links 33 retract the slides 8, thereby carrying the folded bed to its housed position beneath the seat of the sofa. In this operation, the front piece 37 is automatically swung to the upright position, thereby hiding the mechanism from view.

While it is preferred to employ the links 33 to automatically shift the bed, as a whole, in the operation of raising or lowering the seat, the invention is not limited to the employment of this expedient. If desired, the links 33 may be omitted and the forward and rearward shifting of the carriage D may be effected by hand. The idea of pivoting the seat at or near its rear edge so that the seat may be moved to a standing position, and housing a folded bed beneath the seat in such relation thereto that the bed may be unfolded, or occupy an unfolded or extended position without the seat interfering with the use of the bed, is an important one, inasmuch as this expedient contributes both to the simplicity of the structure and the sanitary effect. From Fig. 1 it will be understood that when the seat is in the standing position and the carriage in the advanced position, the seat is locked, or braced, against accidental descent. This feature is of importance, contributing as it does to the safe use of the structure.

The foregoing detailed description has been given for clearness of understanding

only, and no undue limitation is to be understood therefrom, but the appended claims are to be construed as broadly as permissible in view of the prior art.

What I regard as new, and desire to secure by Letters Patent, is—

1. In means of the character set forth, the combination of a frame, a back mounted thereon, a rearwardly swinging seat mounted in said frame and adapted to assume a standing position adjacent said back, and a bodily shiftable folded bed normally housed in said frame beneath said seat and mounted to move forward as a whole with relation to said frame, said folded bed comprising a plurality of bed-sections normally occupying a folded relation with reference to each other and adapted to be shifted forwardly and to unfold forwardly in converting to bed form.

2. In a structure of the character set forth, the combination of a frame, a rearwardly swinging seat, a forwardly movable carriage, and a folded bed comprising a plurality of bed sections independent of said seat and mounted on said carriage and normally housed beneath said seat.

3. In means of the character set forth, the combination of a frame having its end portions equipped with run-ways, a carriage mounted in said run-ways, a rearwardly swinging seat, a normally depressed rear bed-frame section, connections between said bed-frame section and said carriage adapted to elevate said bed-frame section, and a foldably related superposed bed-section, said bed-sections normally housed beneath said seat when the latter is in its normal position for use as a seat.

4. In a structure of the character set forth, the combination of a frame, a rearwardly swinging seat, a pair of normally retracted slides connected with the ends of said frame, a normally depressed rear bed-frame section, links connecting said bed-frame section and said slides adapted to elevate said bed-frame section, and a foldably related front bed-frame section superposed above said first-named bed-frame section, said bed-frame sections normally housed within said frame beneath said seat.

5. In a structure of the character set forth, the combination of a frame having end-standards, guides connected with the lower portions of said end-standards, a rearwardly swinging seat mounted in said frame above said guides, slides movable in said guides, and a folded bed-frame having a rear section raisably mounted on said slides and normally occupying a position adjacent to said slides, and having also a front section foldably related to the rear section, said sections being normally housed in said frame beneath said seat.

6. In a structure of the character set forth,

the combination of a frame, a rearwardly swinging seat, slides connected with said frame, links pivotally connected to said slides, a folded bed-frame having a section pivotally connected with said links, and springs aiding in the elevation of said links and the projection of said slide.

7. In a structure of the character set forth, the combination of a main frame having end-standards equipped on their inner surfaces near their lower ends with guide members provided with slots, slides equipped with rollers extending through said slots, a pivotally mounted seat, links pivotally joined to said slides, and a folded bed having a section pivotally joined to said links, said folded bed being normally housed beneath said seat.

8. In a structure of the character set forth, the combination of a frame, a pivotally supported seat, a forwardly movable carriage supported on said frame, a folded bed having a section raisably mounted on said carriage, and a movable front piece connected with the frame beneath said seat and connected also with said carriage, whereby the front piece will be moved out of the way when the carriage is moved forwardly.

9. In a structure of the character set forth, the combination of a frame, a seat movably mounted in said frame, a forwardly movable carriage mounted on said frame beneath said seat, links pivotally connected with said carriage, a bed-frame section mounted on said links, a bed-frame section foldably connected with said first-named section, and links joining said second-named bed-frame section to said first-named links.

10. In a structure of the character set forth, the combination of a frame, a rearwardly swinging seat, a forwardly movable carriage, and a bed-frame mounted on said carriage and housed beneath said seat, said bed-frame comprising a liftable rear section, a front section, and an intermediate relatively short section pivotally connected with said rear and front sections and with said carriage.

11. In a structure of the character set forth, the combination of a frame, a rearwardly swinging seat, two-pairs of pivotally supported links mounted on said frame, a rear bed-section pivotally connected with the upper portions of said links and adapted to project in front of the front pair of links in the extended position, a short intermediate bed-section pivotally connected with the front end of said first-named bed-section and adapted to be supported thereon by cantilever action in the extended position, and a front bed-section pivotally connected with the intermediate bed-section and equipped with legs adapted to support its front portion in the extended position.

12. In a structure of the character set

forth, the combination of a frame, two pairs of pivoted links mounted on said frame, a rear bed-section pivotally connected with said links and projecting in front of the front pair of links in the extended position, an intermediate bed-section pivotally connected with said first-named bed-section, a front bed-section pivotally connected with said intermediate bed-section, and a U-shaped truss connected with the end members of said intermediate bed-section.

13. In a structure of the character set forth, the combination of a frame, two pairs of pivoted links mounted on said frame, a rear bed-section pivotally connected with said links and projecting in front of the front pair of links in the extended position, an intermediate bed-section pivotally connected with said first-named bed-section, a front bed-section pivotally connected with said intermediate bed-section, and a U-shaped truss pivotally connected with the end members of said intermediate bed-section.

14. In a structure of the character set forth, the combination of a frame, a seat pivotally connected therewith, slides movably mounted on said frame, links connected with said slides, a U-shaped rear bed-section carried by said links, a U-shaped front bed-section, an intermediate bed-section pivotally connected with the arms of said rear and front bed-sections, and a U-shaped truss pivotally connected with the end members of said intermediate bed-section.

15. In a structure of the character set forth, the combination with a frame, of pivoted links mounted thereon, a rear bed-section mounted on said links, a front bed-section, legs pivotally joined to said front bed-section, an intermediate bed-section pivotally connected with the front and rear bed-sections, links connecting said legs with said intermediate bed-section, and links connecting said intermediate bed-section with said first-named links.

16. In a structure of the character set forth, the combination of a supporting frame, a rearwardly swinging seat, a forwardly shiftable folded bed normally housed beneath said seat, and means operative in the movement of said seat to automatically shift said bed forwardly.

17. In a structure of the character set forth, the combination of a frame, a rearwardly swinging pivoted seat, a carriage mounted on said frame, a folded bed mounted on said carriage and normally housed beneath said seat, and seat-actuated means serving to shift said carriage during the movement of said seat.

18. In a structure of the character set forth, the combination of a frame, a rearwardly swinging seat pivotally supported near its rear edge on said frame, a for-

wardly shiftable folded bed normally housed beneath said seat, and links connected with said seat in the rear of its pivotal supports and serving, in the actuation of the seat, to shift said bed.

19. In a structure of the character set forth, the combination of a frame, a seat having pivotal connections near its rear edge with said frame, slides within said frame mounted to move forwardly with relation thereto, a folded bed mounted on said slides and normally housed beneath said seat, and links connecting the front portions of said slides with the rear portion of said seat.

20. In a structure of the character set forth, the combination of a frame, a rearwardly swinging seat mounted on said frame, a pair of horizontally movable slides mounted on said frame beneath said seat and equipped with stops, links pivotally connected with said slides, a rear bed-section pivotally connected with said links and normally supported in a depressed position on said stops, and a front bed-section superposed above and foldably related to said first-named bed-section and carried therewith in the movement of said slides.

21. In a structure of the character set forth, the combination of a main frame, a movably connected front piece therefor, a forwardly movable carriage, a swinging seat, and a folded bed-frame mounted on said carriage and normally housed beneath said seat back of said front piece.

22. In a structure of the character set forth, the combination of a main frame, a rearwardly swinging seat, a forwardly and downwardly swinging front piece beneath said seat, and a folded bed normally housed beneath said seat in the rear of said front piece, said front piece swinging to permit the structure to be converted from sofa form to bed form.

23. In a structure of the character set forth, the combination of a frame, a rearwardly swinging seat adapted to assume a standing position, a forwardly unfoldable bed normally housed in a folded condition beneath said seat and comprising a plurality of bed-sections, and connections between said folded bed and seat adapted to secure the seat in standing position when the bed is extended.

24. In a structure of the character set forth, the combination of a frame comprising end-

standards and a sofa-back fixedly secured between the rear portions of said end-standards, a rearwardly swinging seat having its rear portion pivotally connected with said end-standards near the lower portion of said back, said seat adapted to assume a standing position adjacent said back, and a folded bed normally housed in said frame beneath said seat, said folded bed comprising a normally depressed rear bed-section and a superposed front bed-section foldably connected therewith and normally occupying an inverted position above the rear bed-section and beneath said seat in the folded condition of the structure.

25. In a structure of the character set forth, the combination of a frame comprising end-standards and a sofa-back fixedly secured between the rear portions of said end-standards, a rearwardly swinging seat located between said end-standards and adapted to assume a standing position adjacent to said back, a forwardly movable carriage, and a folded bed mounted on said carriage and normally housed in said frame beneath said seat, said folded bed comprising a normally depressed rear bed-section and a superposed front bed-section foldably connected therewith and normally occupying an inverted position above the rear bed-section and beneath said seat in the folded condition of the structure.

26. In a structure of the character set forth, the combination of a frame having end-standards, a forwardly movable carriage between said end-standards, a rearwardly swinging seat located between said end-standards, and a folded bed mounted on said carriage and normally housed beneath said seat, said bed comprising a rear bed-section raisably mounted on said carriage and a front bed-section foldably related to said rear section.

27. In a structure of the character set forth, the combination of a frame, a forwardly shiftable carriage, a seat connected at its rear portion to said carriage and adapted to swing rearwardly, and a folded bed mounted on said carriage and adapted to move forward therewith and unfold to bed-form.

SOLOMON KARPEN.
